UNITED STATES PATENT OFFICE.

RUDOLF GOLDSCHMIDT, OF BERLIN, GERMANY, ASSIGNOR TO DET TEKNISKE FORSØGS-
AKTIESELSKAB, OF CHARLOTTENLUND, DENMARK.

PERCUSSIVE TOOL.

Application filed May 8, 1923. Serial No. 637,559.

To all whom it may concern:

Be it known that I, RUDOLF GOLDSCHMIDT, a citizen of Germany, and a resident of Berlin, Germany, have invented certain new and useful Improvements in Percussive Tools (for which I have filed an application in Germany on April 25, 1922), of which the following is a specification.

This invention relates to percussive tools 10 of the type in which a hammer rotatable on its axis is reciprocated by the centrifugal action of weights revolubly mounted on the hammer.

According to the present invention the 15 weights are so mounted upon the hammer that they effect a turning or oscillatory movement of the hammer about its own axis. Such turning or oscillatory movement may be transmitted to the tool by the 20 hammer direct or through the hammer casing or through the medium of a flexible diaphragm in the casing so as either to oscillate the tool in both directions or cause it to rotate step-wise.

In order that the invention may be more 25 clearly understood, reference is hereinafter made to the accompanying drawings wherein:

Fig. 1 is a diagrammatic illustration of 30 a simple form of known percussive tool.

Fig. 2 is a sectional elevation on line 2—2 of Figure 3 of one form of percussive tool according to the invention and Fig. 3 is a 35 transverse section on the line 3—3 of Fig. 2.

Fig. 4 is a side view of a modified form 40 of percussive tool.

Fig. 5 shows a longitudinal section of the end of a further construction on line 45 5—5 of Figure 6 and Fig. 6 is an end view thereof.

Figs. 7 and 8 are views corresponding to Figs. 2 and 3 showing a still further modification.

Fig. 9 is a detail view hereinafter mentioned.

Fig. 10 is a fragmentary longitudinal section of a further construction and Fig. 11 is a transverse sectional view taken on line 11—11 of Figure 10.

Referring to Fig. 1, *a* represents a hammer fitted with rotating centrifugal weights *o'*, *o''* the centrifugal action of which reciprocates the hammer *a*. When two oppositely rotating weights *o'* and *o''* are provided,

their centrifugal forces *R'* and *R''* combine to form a resultant *R* which coincides with the direction of reciprocation. The hammer *a* can be set in progressive reciprocation by providing a stop or buffer *d* and a spring *f* whereby a uni-directional force is impressed upon the hammer *a*. The energy stored in the hammer *a* is dissipated by the blow upon the tool or work piece *g*. The inertia of the hammer *a* has to be overcome by the kinetic energy of the weights *o'* and *o''* and it is therefore desirable to keep the inertia of the body *a* small and to make the weights *o'* and *o''* relatively large. In applying such a device to an impact tool it is also important that the hammer should be so constructed that the work stored therein is given up to the tool during impact with as little internal vibration and bending stress as possible. It is also necessary that the complete tool should be so constructed that movable and driven parts and the friction due to their movement should be eliminated as far as possible. It is the object of the present invention to construct the device accordingly.

Fig. 2 illustrates a percussive tool or mechanical hammer. *c* is a casing enclosing the mechanism and mounted upon a support *g*, *m* is a driving motor and *b* a flexible coupling between the motor shaft *e* and the driven shaft *h*. The shaft *h* is movable axially relative to the hammer *a* which transmits the blow to the tool *n* through a member *g* held by a diaphragm *r*, which also serves to make the casing *c* oil-tight.

It is obvious that the centrifugal weights *o'* and *o''* (Fig. 1) cannot conveniently be arranged in the same plane, and in Fig. 2 therefore the hammer *a* carries two light hollow journals *k* about which the centrifugal weights *o'* and *o''* rotate. The weights are integral with bevel gears *i*—*i* which are driven in opposite directions by bevel gear *i'*. The bevel gear *i'* is integral with a bush *h'* and is journaled on a stub shaft *i''* and retained thereon by a collar *i'''*. It is splined to the shaft *h*. The centrifugal forces *R'* and *R''* (Fig. 3) of the weights now constitute a pair of forces which change in direction and magnitude according to the position of the centrifugal weights and tend to impart a swinging motion to the hammer *a* about its own axis *z*—*z*. This turning

movement may be transmitted to the casing and support by mounting the trunnions *k* so as to roll or slide at *l* in a groove *l'* in the casing. In hand hammers this turning movement is usually transmitted to the operator's hand, the vibrations thereby transmitted to the hand or support being mitigated by springs. These vibrations can be entirely overcome if, as shown in Fig. 4, 10 the hand grip is rotatably mounted on the hammer casing.

In percussive boring tools the turning movement can be utilized with advantage in order to turn the percussive boring tool 15 about its axis. In the form shown in Fig. 4 the hand grip *p* is rotatably attached at *A* to the motor casing *m* and allows the whole casing together with the boring tool *n* to oscillate about its longitudinal axis *z-z*. In 20 order to reduce the oscillating mass, the motor casing *m* may be rotatably attached to the hammer casing *c* at *B* and the motor casing *m* may be fixed at *A* to the hand grip *P*. Such an arrangement is shown in Fig. 7. 25 The turning movement may be increased if, for example, the moment created by the centrifugal weights is not sufficient to turn the boring tool. This may be effected by utilizing the work stored in the mass of the 30 oscillating hammer *a* to produce transverse blows on the tool. The tool *n* may thus not only be fed forward in the direction of the axis *z-z* but it may be rotated about this axis by impact. The transverse blow may 35 either be imparted to the casing by fitting the boring tool in a hexagonal or splined socket, or the casing may oscillate and rotate with the hammer and the blow be transmitted from the casing to the tool, or the 40 hammer may act directly upon the boring tool.

Fig. 5 shows an arrangement wherein the casing is assumed to swing with the hammer *a*. In this case the casing *c* transmits the 45 traverse blow to the boring tool *n*. This construction only differs from Fig. 2 in that the shaft *s* of the boring tool is mounted rotatably in the head of the casing and carries two segmental projections *t* which engage two segments *v* projecting from the 50 casing *c*. Between the two pairs of segments are springs *u*. When the casing swings in the direction I, the springs are compressed (assuming that the strength of the springs 55 is less than the grip of the work on the boring tool). When the casing swings in the opposite direction II, the energy is dissipated in the blow upon the faces *w* of the segments *t* and is sufficient to turn the boring tool stepwise in the direction II.

Figs. 7 and 8 illustrate an arrangement 60 wherein the boring tool is non-rotatably mounted in the casing, the transverse blow being effected inside the casing. In the casing are two guides *x* against which strike

the trunnions *k* on the hammer *a*. A spring *f* is compressed during the backward movement of the hammer *a*, this spring being fastened at one end at *f'* to one of the trunnions *k* and at the other end at *f''* to a fixed collar 70 in the casing *c*. It thus fulfills the double purpose of a compression spring both for the longitudinal impact and also for the transverse impact.

Instead of transmitting the transverse impact through the medium of the casing to the boring tool, it may be transmitted direct to the tool *n* by the aid of the intermediate member *q* of the diaphragm *r* as in Figs. 10 and 11, wherein the intermediate member *q* carries projections *q'* and *q''* for guiding the hammer *a* and tool *n* respectively, the guide *q'* having segmental recesses adapted to receive segments *y* on the hammer *a*. The diaphragm *r* in this arrangement must be so shaped that it not only yields in the direction *z-z*, but may yield to torsion under the transverse blow. For this purpose it may be cup-shaped, or 85 corrugated. The material of the diaphragm is preferably oil-proof impregnated leather. On stepwise rotation of the tool *n* by the transverse blow the freely rotatable casing will slowly follow up, being carried by the diaphragm. The re-action of the oscillations of the hammer *a* about its axis are also taken up (as in Fig. 7) by the spring *f* which transmits the re-action to the casing *c* and from thence through the flexible diaphragm *r* to the boring tool *n* which is sufficiently held by grip of the work. 100

If one end of the spring *f* is not secured at *f''* to the hammer casing *c* but at *e* as in Fig. 9 to the motor casing *m*, the casing must be allowed to rotate at the same speed as the tool in order to keep the spring constantly under tension. In this arrangement, therefore the angular velocity of the motor casing or rotatable part thereof, for example, a rotating end cap, and consequently 110 that of the boring tool may be regulated within certain limits.

Claims—

1. A percussive tool comprising the combination of a hammer, means for supporting said hammer for longitudinal and rotary movement, centrifugal weights revolvably mounted on said hammer in such manner as to subject said hammer both to longitudinal reciprocation and oscillation about its longitudinal axis and mechanism for revolving said weights. 115

2. A percussive tool comprising the combination of a hammer, a casing therefor, means for supporting said hammer in said casing for longitudinal movement therein and for rotary movement, centrifugal weights revolvably mounted in said casing and on the hammer in such manner as to subject the hammer to longitudinal recipro- 125

cation whilst oscillating said hammer about the longitudinal axis, and mechanism for revolving said weights.

3. A percussive tool as specified in claim 5 2 having means for revolubly supporting the casing.

4. A percussive hand tool as specified in claim 2 having a hand grip to which the hammer casing is rotatably connected.

10 5. A percussive tool as specified in claim 1 in which both the longitudinal and oscillatory movement of the hammer is transmitted to a rotary tool.

15 6. A percussive tool as specified in claim 1 having means whereby the oscillatory movement of the hammer effects stepwise rotation of a rotary tool.

20 7. A percussive tool as specified in claim 1 having a casing enclosing the hammer and weights, a tool supported by said casing and means interposed between said tool and hammer whereby the hammer imparts a forward blow to the tool and oscillation thereof.

25 8. A percussive tool as specified in claim 2 having a tool supported by the casing and means whereby said casing effects stepwise rotation of said tool.

30 9. A percussive tool as specified in claim 1 having a spring against which the hammer reacts during its oscillation.

10. A percussive tool as specified in claim

1 having a spring against which the hammer reacts both during its oscillation and reciprocation.

11. A percussive tool as specified in claim 35 2 having a coil spring connected at one end to the hammer and at the other end to the casing.

12. A percussive tool as specified in claim 2 in which the casing is revoluble and in 40 which a spring is connected at one end to the hammer and at the other end to the casing.

13. A percussive tool comprising the combination of a hammer, a casing enclosing the 45 hammer, means for supporting said casing for longitudinal movement therein and for rotary movement, abutments for limiting oscillation of said hammer in said casing, centrifugal weights revolubly mounted in said 50 casing and on the hammer for subjecting said hammer to reciprocation and oscillation, means for revolubly supporting said casing, a tool supported to turn with said casing and a member fluid-tight in said cas- 55 ing between said tool and hammer.

14. A percussive tool as specified in claim 13 having a spring between the hammer and casing and connected thereto.

In testimony whereof I hereunto affix my 60 signature.

RUDOLF GOLDSCHMIDT.
